UNITED STATES PATENT OFFICE

HARRY A. HOKE, OF ALTOONA, PENNSYLVANIA

LOCOMOTIVE TENDER

Application filed February 5, 1932. Serial No. 591,049.

This invention relates to locomotive tenders, and more particularly to water bottom frames for such tenders and to the manner in which feed water is supplied to the locomotive.

Heretofore water bottom frames for tenders have been employed in which the water feeding channels or troughs leading to the front end of the tender have been disposed in level relation to the rails, and in which the tank valves, through which feed water is supplied to the locomotive, have been located at the front end of the tender with their intake passages projecting vertically downward from the water bottom frame. With the use of such constructions, when the tender is standing on a sloping track with its rear end down, it is evident that a considerable amount of water is not available to the injectors for use in the locomotive boiler. Furthermore, on account of the location of the pipes on the locomotive leading to the injectors, and on account of the fact that locomotives are operated over track having considerable curvature, it is not practical to move or lower the hose connections between such pipes and the tender tank valves.

Accordingly, the principal object of the present invention is to provide a water bottom tender frame and connections to a locomotive so designed and arranged as to render more water available to the injectors when the tender is on a sloping track, without causing the fittings comprising the connections between the tender tank and locomotive to encroach upon the necessary areas of clearance above the track, and thus to overcome the aforementioned difficulties.

Other more specific objects and advantages characterizing my invention will become more fully apparent from the detailed description of one example or embodiment thereof which follows hereinafter, having reference to the accompanying drawings.

Of the drawings:

Fig. I is a side elevation of a tender constructed in the manner of my invention, showing at the front end of the tender the connecting hose leading to the locomotive and

showing also the injector feed pipe on the locomotive.

Fig. II is an enlarged side elevation of the front end of the water bottom frame of the tender of Fig. I.

Fig. III is a plan view of the same.

Fig. IV is a front end view of the same, with the left-hand portion shown in section, as indicated by the lines IV—IV of Fig. III.

Fig. V is a longitudinal cross-section of the same, taken as indicated by the lines V—V of Fig. III.

Fig. VI is a cross-section of one of the front end chambers of the frame, showing the manner in which a tank valve is mounted thereon, the section being taken as indicated by the lines VI—VI of Fig. II.

Fig. VII is a cross-section of the water bottom frame, taken transversely of the tender as indicated by the lines VII—VII of Fig. I; and,

Fig. VIII is a rear end view of the water bottom frame with the right-hand portion shown in section as indicated by the lines VIII—VIII of Fig. I.

With particular reference to Fig. I of the drawings, there is shown a locomotive tender similar as to superstructure to tenders now in use and including a water space, designated at A, and a coal space designated at B, separated transversely by a slope sheet 1. It will be understood that according to the usual practice, the water tank defined by the sides of the tender extends forward in advance of the slope sheet 1; and that the coal space B, which is at the forward end, is bounded at its sides by forwardly extending wings of the water tank. The water bottom frame, upon which the water tank A is supported, is comprehensively designated at 2. Depending from the frame 2 there is shown a water scoop 3 of conventional design.

While the water tank proper A is supported upon trucks, the wheels of which are diagrammatically indicated at 4, in parallel relation to the rails, it will be especially noted that the water bottom frame 2 slopes downwardly toward the front end of the tender, and there terminates in depressed chambers 5 at each side of the center line of the tender.

To the front end chambers 5, tank valves 6 are fitted having the usual hose connections 7 which join the injector feed pipes 8 on the locomotive.

5 As shown in Figs. II and III, and in the various transverse sections of the water bottom frame 2 of the remaining figures of the drawings, the frame 2 is made up of a single casting including a center sill member 9, 10 bolsters 10 and 11, end sills 12 and 13, and side channels or troughs 14. The construction of the center sill member 9, as well as that of the bolsters 10, 11 is generally similar to that of tender frames now in general use, 15 and, therefore, need not be described in detail. At the forward end of the tender, the center sill member 9 terminates in a wearing plate 15, and is formed adjacent thereto with a fulcrum pin housing 16 of common construction. The usual center plate 17 for the forward truck is provided at the point where the center sill member 9 joins the front end bolster 10, as shown in Figs. IV and V, and a similar center plate 18 for the rear truck 20 is formed at the rear bolster 11, as shown in Fig. VIII. The web portions 19 and 20 of the front and rear bolsters, respectively 10 and 11, merge at their outer ends with the side channels 14. The side channels 14 extend 25 from one end of the tender to the other and are depressed below the other portions of the water bottom frame 2.

At the front end of the water bottom frame 2, as shown in Fig. III, flat plate members 35 21 and 22 are formed integral with the frame between the center sill 9 and the side channels 14, the plate members 21 and 22 serving as the bottom of the water tank at that region of the tender. The side channels 14 merge 40 with the front end sill 12 forming the chambers 5 which are directed diagonally inward toward the center line of the tender. At each side of the center sill 9, the frame 2 is formed with upstanding flanges 23 to the 45 marginal edges of which there are riveted the plates which comprise the sides of the coal space B. The floor of the coal space B is indicated at 24 in Fig. I.

At the rear end of the tender and at the 50 intermediate portion, the water frame 2 has cast integral therewith flat plates, such as 25 and 26 in Fig. VII, which form the bottom of the water tank in these regions. Upstanding projections, such as 55 shown at 27 and 28, on the flat plates 25 and 26, serve as attachments to which vertical tank braces are anchored.

Throughout the length of the tender, side plates 29 are riveted to the vertical flanges 60 30 of the side channels 14. In the present example of the invention, the cross-section of each side channel 14 changes in form from one region of the frame 2 to another, as illustrated in Figs. IV, VII and VIII. The 65 bottom members 31 of the side channels 14

are flat continuous plates sloping with gradual inclination from the rear of the tender toward the front end. At each transverse section of the frame, the bottom members 31 of the side channels 14 represent the lowest points of the water carrying space of the tender; and the front end chambers 5, to which the side channels 14 lead, are still further depressed, and constitute the parts of the water bottom frame which are nearest to the rails. It will be particularly noted that, while the side channels 14 slope downward toward the front end of the tender, the center sill member 9 is supported on the tender trucks in parallel relation to the rails; and the various plates 21, 22, 24, 25, 26, which form the major portion of the tank bottom, are likewise parallel to the rails. Thus the side channels 14 serve as water feeding troughs, rendering more water available to the locomotive injectors when the tender is standing on a sloping track with the rear end down, but the side channels are so formed with respect to the remainder of the water bottom frame as not to require a material departure from standard practice with regard to the general construction of the frame.

In Fig. VI there is shown an enlarged sectional view of one of the tank valves 6 located at the front end of the tender, showing the manner in which the valve is applied to a front end chamber 5 which forms the terminus of the corresponding side channel 14. At the bottom of each chamber 5, a threaded plug 32 is screwed into a correspondingly threaded opening and serves as a means of rendering ready access to the chamber for the purpose of draining or washing out the chamber. The tank valve 6, as represented in the present example of the invention, is a valve of ordinary construction comprising a valve member 33 seated within the intake passage 34 and operated through an operating shaft 35 and a handle 36. When the handle 36 is turned to engagement with a pin 37, water flows in the direction indicated by the arrow through the intake passage 34, and the discharge passage 38 to the flexible hose 7, and from thence to the injector feed pipes 8 on the locomotive. A screen 39 is preferably provided within each chamber 5 at the point where the tank valve 6 is fitted thereto. In contradistinction to the usual practice of applying a tank valve to a water bottom frame with the intake passage disposed vertically beneath the end of the frame, the tank valve 6 of this invention is applied with its intake passage 34 disposed in a horizontal plane. Accordingly, though the vertical distance between the bottom of each chamber 5 and the top surface of the rails has been lessened by the downward sloping of the side channels of the frame, the

hose connections 7 are still maintained at the customary height above the rails.

From the above description it will be apparent that the novel design of the water bottom frame of this invention with its forwardly and downwardly sloping side channels 14 and the novel manner in which the tank valves are applied to the front end of the frame overcome difficulties characteristic of older constructions, occasioned when a tender is on an upgrade, and result in more water being available to the locomotive injectors without lessening the clearance between the bottom of the tender frame and the underlying track.

While I have described one form or example which my invention may take and have referred to certain specific features of construction, it will be apparent that various changes may be made in the particular form of tender herein selected as an example of the practice of the invention, without departing from the spirit of the invention as defined in the annexed claims.

Having thus described my invention, I claim:

1. In a locomotive tender, a frame including a water bottom sloping downward toward the front of the tender throughout substantially the length thereof.

2. In a locomotive tender, a tank, and a frame for supporting said tank in parallel relation to the rails, said frame including a water bottom sloping downward toward the front of the tender throughout substantially the length thereof.

3. In a locomotive tender, a tank, and a frame for supporting said tank, said frame having integral therewith a channel serving as a water trough and sloping downward toward the front of the tender.

4. In a locomotive tender, a tank, and a frame including in one piece a center sill member for supporting said tank in parallel relation to the rails and side channels serving as water troughs and sloping downward toward the front of the tender.

5. In a locomotive tender, a water bottom sloping downward toward the front of the tender, and a valve controlling the supply of water to the locomotive applied to the lowermost part of said water bottom.

6. In a locomotive tender, a water bottom sloping downward toward the front of the tender, and an outlet valve controlling the supply of water to the locomotive, said valve being disposed at the front end of said water bottom with its intake passage substantially horizontal.

60 7. In a locomotive tender, a water bottom sloping downward toward the front of the tender and terminating in a depressed chamber, a tank valve connected to the side of said chamber, and a drain at the bottom of said chamber.

8. In a locomotive tender, a tank, a frame including in one piece a center sill member for supporting said tank and side channels serving as water troughs and sloping downward toward the front of the tender, said channels terminating in depressed chambers at each side of the tender, and tank valves at said depressed chambers disposed with their intake passages substantially horizontal.

9. In a locomotive tender, a tank, a frame having a center sill and plates thereon forming the bottom of said tank, channels at the sides of said frame serving as water troughs and sloping downward toward the front of the tender, said channels terminating in depressed chambers at the lowermost part of said frame, and tank valves at said depressed chambers disposed with their intake passages substantially horizontal.

10. In a locomotive tender, a tank, a frame having a center sill parallel to the rails and plate members thereon defining in part the bottom of said tank, channels at the sides of said frames serving as water troughs at the bottom of said tank and sloping downward toward the front end of the tender, said center sill, plate members and side channels being cast integral with the frame aforesaid.

In testimony whereof, I have hereunto signed my name at Altoona, Pennsylvania, this 2nd day of February, 1932.

HARRY A. HOKE.
